United States Patent

Des. 234,601
Patented Mar. 25, 1975

234,601

ELECTRICAL RELAY OR SIMILAR ARTICLE

Ewart S. Hague, Cranston, R.I., and Larry W. Shaw,
Norton, Mass., assignors to Texas Instruments Incorporated,
Dallas, Tex.

Filed Feb. 23, 1972, Ser. No. 228,793

Term of patent 14 years

Int. Cl. D13—03

U.S. Cl. D26—13 R

Fig. 1.

Fig. 2.

Fig. 3.

Fig. 6.

Fig. 5.

Fig. 4.

Fig. 7.

Fig. 8.

FIG. 1 is a top plan view of an electrical relay or similar article, showing our design;

FIG. 2 is a front plan view thereof;

FIG. 3 is a bottom plan view of the article;

FIG. 4 is a right side view thereof;

FIG. 5 is a rear plan view thereof;

FIG. 6 is a left side view thereof;

FIG. 7 is a perspective view as seen from the top, front and one side; and

FIG. 8 is a perspective view as seen from the bottom, back and another side.

We claim:

The ornamental design for an electrical relay or similar article, substantially as shown and described.
